UNITED STATES PATENT OFFICE.

ALBERT J. DAWSON, OF PORTSMOUTH, NEW HAMPSHIRE.

DAVIT.

1,364,727.

Specification of Letters Patent.

Patented Jan. 4, 1921.

Application filed June 9, 1920. Serial No. 387,679.

To all whom it may concern:

Be it known that I, ALBERT J. DAWSON, a citizen of the United States, and a resident of Portsmouth, in the county of Rockingham and State of New Hampshire, have invented a new and Improved Davit, of which the following is a full, clear, and exact description.

This invention relates to improvements in davits, and more particularly to balanced davits, an object of the invention being to provide an improved construction of davit, mounting therefor, and operating means therefor, which result in balancing the weight of the boat so as to reduce to a minimum the power necessary to swing the boat from an inboard to an outboard position, and vice versa.

A further object its to provide improved davits which can be quickly and easily operated to move the lifeboats from one position to another and provide a strong and durable support for the lifeboats so that they may be safely lowered to the water.

25 A further object is to provide an improved construction and operating means for davits which may be utilized for other purposes than supports for lifeboats as the mechanism is capable of adaptation for 30 transporting or moving loads from one position to another.

With these and other objects in view the invention consists in certain novel features of construction, and combinations and arrangements of parts, as will be more fully hereinafter described and pointed out in the claims.

In the accompanying drawings:—

Figure 1 is a view in transverse section 40 through a portion of a ship illustrating in full lines my improved construction of davit and operating means, showing the parts with the lifeboat in inboard position, and in dotted lines illustrating an intermediate position, and in dot and dash lines a full outboard position.

Fig. 2 is a view in side elevation of Fig. 1.

1 represents the hull of a ship and in the drawings I have illustrated but a fragment 50 of the side of the hull at its point of attachment with the strengthening deck 2, and 3 is the boat deck located above deck 2 as is common in the art.

4, 4, represent my improved davits which 55 are pivotally connected at their lower ends, as shown at 5, to brackets 6, the latter fixed

to the hull 1 at its point of juncture with the deck 2 so that the strains of the davit are sustained by the hull structure.

In normal position the upper ends of the 60 davits 4 curve inwardly and support levers 7. These levers 7 are made of two parts or of a single part connected by an integral pivot 8 which is mounted to turn in the upper end of the davit so that while the 65 main or longer end of the lever 7 is on one side of the davit, the shorter end 9 of the lever is on the other side of the davit and the shorter ends of the two levers are located between the pair of davits and provided 70 support for the lifeboat 10, said supporting means being indicated at 11 and constituting the ordinary arrangement of ropes and tackle as is common in the art.

On the boat deck stringer 12 I provide 75 any desired number of supporting brackets 13 in which a shaft 14 has rotary mounting and provide on this shaft 14 a pair of crank arms 15 having their free ends pivotally connected with the levers 7 by means 80 of links 16. The links 16 are pivotally connected to the free ends of the arms 15 by means of pivot pins or other suitable devices 17 and are pivotally connected to the levers 7 by pivot pins or other suitable connections 85 18. Links 19 pivotally connect the pivot pins 17 with pivot pins 20 supported by the intermediate portions of the davits 4, as clearly shown in Fig. 1.

The shaft 14 may be turned by any suitable mechanism to control the operation thereof manually. I have illustrated as a means for operating this shaft 14 a pair of intermeshing gears 21 and 22, the former fixed to the shaft 14 and the latter carried 95 by a crank shaft 23 having a crank arm 24 to turn the same.

The operation is as follows: The load is supported from the free ends of the shorter members 9 of levers 7. When the shaft 14 100 is turned in the proper direction, it will cause the crank arms 15 to swing upwardly and outwardly. At the same time, through the medium of the links 16, this motion will be imparted to the levers 7 which will swing 105 to the position shown in dotted lines in Fig. 1, and at the same time, the links 19, through the medium of their connection with the crank arms 15, will compel the davits 4 to swing outwardly so that the parts will occupy the position indicated in dotted lines 110 in Fig. 1. A continued movement of the

shaft 14 in the same direction will move the parts to the position indicated in dot and dash line in Fig. 1, which will be the full outboard position ready for lowering the boat.

During the travel of the parts from one extreme position to another, it will be noted that the levers 7 are swung entirely around so that their pivot points 18 move in the arc 10 of a circle approximating one hundred and eighty degrees, but the boat is carried in a comparatively straight path from one extreme position to another.

By virtue of the eccentricity of the load 15 from a vertical through the pivot point 8, a counterbalancing force acting at the pivot point 18 is had, which is transmitted to the pivot point 17 by means of the link 16. This force tends to revolve the cranks 15 in a 20 counterclockwise direction. Now by virtue of the load at the outer end of the members 9, this counteracting force at the pivot point 18 has a reaction at the pivot point 8, which, coupled with its eccentricity from a vertical 25 through the pivot point 5, has a tendency to revolve the davit about the pivot 5 in a clockwise direction, which tendency is transmitted by the links 19 to the crank arms 15 at the pivot points 17. We have therefore 30 two opposite forces acting on the cranks 15 at the pivot points 17 and in order to operate the davit, we have only to overcome the difference of the two forces plus the power necessary to overcome the friction of the 35 bearings. In other words, the two forces have a balancing tendency, hence, I refer to my improved davit as a balancing davit.

The operation may also be described as a 40 double or counterpoint toggle joint having one arm in common and being acted upon by two forces having opposite components. During the operation of the davit, the vertical movement of the free ends of the lever members 9 is always opposite to the vertical 45 movement of the pivot point 8 with the result that the boat moves in a straight or flat path which is the travel of the load, and there is also a slight vertical travel which means but a comparatively small total 50 amount of work is done by the process of transporting the load from inboard to outboard position.

As the davits are pivotally connected to the strength deck of the vessel, or rather to 55 the hull at the point of juncture with the strength deck, the strains and compression stresses are transferred directly to the hull proper and not to the lightly constructed boat deck as is common with davits in general use, and as the shaft 14 is located on the boat deck stringer, the latter needs but little special foundation work.

It is obvious that the proportions of the several parts may be varied so as to describe 60 different arcs or length of arc in movement,

and hence I do not wish to limit myself to the precise details set forth, but consider myself at liberty to make such changes and alterations as fairly fall within the spirit and scope of the appended claims.

70

I claim:

1. The combination with a ship, of davits pivotally connected to the ship, levers pivotally connected between their ends to the free ends of the davits, said levers adapted 75 at one end to support a lifeboat, and a crank shaft operatively connected to the davits and also to the levers for moving the davits on their pivots and simultaneously swinging the levers on their pivots.

80

2. The combination with a ship, of davits pivotally connected at their lower ends to the ship at a point below the boat deck, a shaft supported on the boat deck, levers pivotally supported between their ends on the 85 free ends of the davits and adapted to support a lifeboat at one end, crank arms secured to the shaft, links connecting said levers with the crank arms, and means connecting the crank arms with the davits.

90

3. The combination with a ship, of davits pivotally connected at their lower ends to the ship at a point below the boat deck, a shaft supported on the boat deck, levers pivotally supported between their ends on the 95 free ends of the davits and adapted to support a lifeboat at one end, crank arms secured to the shaft, links connecting said levers with the crank arms, and links pivotally connecting the crank arms with intermediate portions of the davits.

100

4. The combination with a ship, of davits pivotally connected at their lower ends to the ship at a point below the boat deck, a shaft supported on the boat deck, levers pivotally supported between their ends on the 105 free ends of the davits and adapted to support a lifeboat at one end, crank arms secured to the shaft, links connecting said levers with the crank arms, and links pivotally connected at one end with the pivotal connections of the crank arms and the links and at their other ends pivotally connected to intermediate portions of the davits.

110

5. The combination with a ship, of davits, brackets pivotally connecting the lower ends of the davits with the hull of the ship, other brackets located on the boat deck, a shaft supported in the last-mentioned brackets, levers fulcrumed between their 120 ends on the free ends of the davits, said levers comprising two members disposed at opposite sides of the davits, crank arms on the shaft, links connecting the crank arms with said levers at one end of the latter, 125 means on the other ends of said levers for supporting a boat, and links pivotally connecting the crank arms with intermediate portions of the davits.

115

6. The combination with a ship, of davits,

130

brackets pivotally connecting the lower ends of the davits with the hull of the ship, other brackets located on the boat deck, a shaft supported in the last-mentioned brackets, 5 levers fulcrumed between their ends on the free ends of the davits, said levers comprising two members disposed at opposite sides of the davits, crank arms on the shaft, links

connecting the crank arms with said levers at one end of the latter, means on the other 10 ends of said levers for supporting a boat, links pivotally connecting the crank arms with intermediate portions of the davits, and means for manually turning the shaft.

ALBERT J. DAWSON.
